(57) **CLAIM**

The ornamental design for a wearable tracking device, as shown and described.

DESCRIPTION

FIG. 1 is a bottom view of a wearable tracking device showing my new design;

FIG. 2 is a side view of the wearable tracking device;

FIG. 3 is an end view of the wearable tracking device;

FIG. 4 is a top view the wearable tracking device;

FIG. 5 is a top perspective view of the wearable tracking device;

FIG. 6 is a bottom view of another embodiment of a wearable tracking device showing my new design;

FIG. 7 is a side view of the wearable tracking device;

FIG. 8 is an end view of the wearable tracking device;

FIG. 9 is top view of the wearable tracking device.

FIG. 10 is a top perspective view of the wearable tracking device;

FIG. 11 is an end view of yet another embodiment of a wearable tracking device showing my new design;

FIG. 12 is a top view of the wearable tracking device;

FIG. 13 is a side view of the wearable tracking device; and, FIG. 14 is a perspective view of the wearable tracking device.

The broken lines showing are included for the purpose of illustrating portions of the article that form no part of the claimed design.
